[57] CLAIM

The ornamental design for an insulating cap for a shielding wire, substantially as shown.

DESCRIPTION

FIG. 1 is a perspective view, as viewed from right, of an insulating cap for a shielding wire showing my new design;

FIG. 2 is a perspective view, as viewed from left, of the insulating cap;

FIG. 3 is a bottom view thereof; and

FIG. 4 is a longitudinal sectional view taken through the center thereof.

FIG. 1

FIG. 2

FIG. 4

FIG. 3
